United States Patent Office

Des. 215,545

Patented Oct. 7, 1969

215,545

ELECTRICAL TERMINAL BLOCK UNIT

Paul Huska, Los Angeles, Calif.
(1551-A 16th St., Santa Monica, Calif. 90404)

Continuation-in-part of design application Ser. No. 7,709,
July 3, 1967. This application Dec. 12, 1968, Ser.
No. 14,940

Term of patent 14 years

Int. Cl. D13—03

U.S. Cl. D26—1

FIG. 1.

FIG. 2.

FIG. 1 is a front perspective view of the electrical terminal block unit embodying my new design.

FIG. 2 is a rear perspective view thereof.

This is a continuation-in-part of design application Ser. No. 7,709, filed July 3, 1967 and now abandoned.

I claim:

The ornamental design for an electrical terminal block unit, as shown and described.
